UNITED STATES PATENT OFFICE.

HOWARD B. SMITH, OF MACON, GEORGIA.

SASH LOCK.

Application filed April 5, 1922. Serial No. 549,702.

To all whom it may concern:

Be it known that I, HOWARD B. SMITH, a citizen of the United States, residing at Macon, in the county of Bibb and State of Georgia, have invented certain new and useful Improvements in Sash Locks, of which the following is a specification, reference being had to the accompanying drawings.

It is the purpose of the present invention 10 to provide a device of this kind which is entirely automatic, that is to say, after releasing hold on the sash locking members. In other words the sash locking members are spring tensioned, and after pressure is released thereon, they automatically engage with the sash guides of the window frame, for holding the sash in different adjusted positions.

Another purpose is the provision of a 20 sash lock, which in addition to its locking features, also takes the place of the sash weights. Furthermore the sash lock is simple, efficient and practical in construction, and can be cheaply made, also can be 25 easily and quickly applied, and when applied acts as an anti-sash rattler, and also eliminates all sash props. In the construction of the lock punch and die work is employed, entirely doing away with casting 30 construction, as well as avoiding sliding parts as well as cover and sash plates. Additionally the present invention obviates the use of gears and other members, which are subjected to friction and wear.

35 A still further purpose is to provide a sash lock which is compact in construction, and furthermore the locking members do not depend upon rivets, to insure strength.

40 A further purpose is the provision of a sash lock, which comprises a carrying plate for the locking members, which are pivotally mounted upon the plate by means of eyelet rivets, which permit the locking members to freely move, there being suitable fastening means such as nails, screws and the like 45 passing through the eyelet rivets and into the stile of the window sash, for the purpose of mounting the lock in place. The purpose of pivotally mounting the locking members 50 by means of eyelet rivets, is to enable the fastening means such as nails, screws and

the like to fasten the lock to the sash, in such wise as to avoid friction between the locking members and the holding plate, and permit the locking members to freely oscillate or move under the action of tensioning means, to cause the locking members to automatically engage the channel or guide groove of the window frame.

55 A still further purpose is the provision of a sash lock, which is positive in its locking action, whether an attempt is made to raise or lower the sash. As will be hereinafter understood the more the sash is moved in either direction perpendicularly, the more 60 secure the sash becomes locked, especially due to the arrangement of the locking members and their digging actions into the window frame. In order to secure this positive 65 locking action, either one of the locking members is capable of striking an abutment which prevents the movement of the member any further than it is required to move.

70 It is to be understood that the particulars herein given are in no way limitative and 75 that while still keeping within the scope of the invention, any desired modifications of detail and desired proportions may be made in the apparatus according to circumstances.

80 The invention comprises further features and combination of parts, as will be herein-after set forth, shown in the drawings and claimed.

85 In the drawings:—

Figure 1 is a view in elevation of a portion of a window frame, and the sash mounted in the usual guides, showing the improved sash lock as applied;

Figure 2 is a view in elevation of a window sash and frame, showing the locking members in released position;

Figure 3 is an enlarged perspective view of the sash lock, more clearly showing its construction;

90 Figure 4 is a view in elevation of a window sash and frame, showing one of the locking members as having come in contact with an abutment, and with the locking member extended into the bottom of the 95 guide channel or groove of the window frame, showing how it is necessary that the 100

locking member must drag through the frame in order to move the sash, which is practically an impossibility;

Figure 5 is a sectional view on line 5—5 of Figure 3;

Figure 6 is a detail view of one of the locking members;

Figure 7 is a detail view of the carrying plate.

10 Referring to the drawings, 1 designates a carrying plate, which may be any suitable shape or size, and may be constructed of any suitable sheet metal, preferably of $\frac{1}{16}$ of an inch in thickness. In fact it is preferable 15 to construct this carrying plate of aluminum, though any other metal, such as steel or brass may be used. Preferably the carrying plate is substantially triangular in formation, and pivotally mounted upon said plate by means 20 of eyelet rivets 2 are locking members 3. Mounted through the carrying plate is an eyelet 4, which is arranged on the plate at a point between the adjacent edges of the locking members 3, thereby not only constituting 25 an abutment for the adjacent edges of the locking members, but also constituting means for the reception of a fastening screw 5, which is in addition to the fastening screws 6 passing through the eyelet rivets previously mentioned. Screws or nails may 30 be used to pass through the eyelets, for holding the lock to the sash, preferably screws, due to the fact that they are more secure.

It will be noted that the locking members 35 3 have their locking ends provided with teeth 8, and when the sash lock is applied to the sash, the locking members engage between the sash retaining strip 9 and the face of the side stile of the sash, whereby the 40 locking toothed ends of the locking members may engage with the bottom of the sash guide groove of the window frame. The locking members 3 are provided with apertures or openings 10, while the carrying 45 plate 1 is provided with similar openings or apertures 11. When the lock is to be applied to a window sash, the locking members are actuated to positions, whereby the openings or apertures 11 may register with the 50 openings or apertures 10. Metal pins, nails or pieces of wire or any other form of instruments 11^a may enter the registering apertures or openings 10 and 11, to hold the locking members 3 in corresponding relative 55 positions. The locking device with the members held in their proper positions may then be fastened to the stile of the window sash, the toothed ends of the locking members having been inserted between the retaining strip and the face of the sash. In other words while the locking members are 60 so disposed with relation to the carrying plate, the lock is arranged adjacent the face of the sash, the toothed ends of the locking members engage in the guide groove, then 65

screws, nails or the like preferably the former are inserted through the eyelets and penetrated into the stile of the window sash. It is obvious that the screws, nails or other fastening means may be driven home very 70 secure, and will not deform the eyelet rivets to an extent as to exert friction on the pivoted locking members.

The larger ends of the locking members, that is to say the ends which are pivoted to 75 the carrying plate are provided with laterally extending ears or finger and thumb pieces 12 and 13. These finger or thumb ears have openings or apertures 14, for the reception of the terminal portions 15 of the 80 bowed spring 16. The bowed portion of this spring (which is preferably constructed of spring wire material) engages the eyelet of the carrying plate, that is to say the centrally disposed eyelet, it being obvious that 85 the eyelet constitutes means for holding the bowed portion of the spring securely in position.

The screws which pass through the eyelet rivets and through the eyelet carried by the 90 carrying plate are not of the flat head type, but are more or less of the button head type of screws. In fact, since the screw which passes through the eyelet of the carrying plate is of the button head type, the head of 95 the screw extends a substantial distance over the margin of the eyelet, so as to overlie the bowed portion of the spring, and insure the prevention of the same disengaging from 100 said eyelet.

After the lock has been applied in the manner above stated, the pins, nails or pieces of wire are withdrawn from the openings 10 and 11, in which case the locking members are free to be actuated, and are free to assume locking engagements with the channels or grooves of the window frame.

In order to move the sash, the thumb and fore finger are applied to the ears of the locking members, in which case the locking members are moved in directions from each other, thereby disengaging their toothed ends from the bottom of the guide groove or channel of the frame. When the locking members are so disengaged from the channel 115 or guide groove of said frame, the sash is free to move perpendicularly in either direction.

If an attempt is made to raise the sash without moving the locking members away 120 from each other, and sufficient pressure applied to cause one or the other of the locking members to move until one of its edges contacts with the center eyelet which receives the main holding screw or nail, further movement of the locking member is 125 prevented. In applying this pressure, the toothed end of the locking member will force itself into the bottom of the channel or guide groove of the window frame, and will 130

practically prevent further movement of the sash. In fact if the sash is forced, when the toothed end of the locking member is embedded or forced into the bottom of the groove, the locking member will have to drag through at least $\frac{1}{8}$ of an inch of the wood of the frame, which is practically impossible. In this way, it is obvious that the sash lock is positive in its action.

In order to raise the sash it is necessary to apply pressure by means of the thumb and fore finger on the opposed thumb and finger pieces or ears 12 and 13, for the purpose of separating the toothed ends of both locking members, in other words to force them further apart. When the locking members are so moved the sash is free to be raised or lowered, and just as soon as pressure upon the thumb and finger pieces is released, the toothed ends of the locking members can engage the bottom of the guide groove or channel of the frame. Pressure is applied upon the thumb and finger pieces with one hand, while the sash may be raised or lowered with the other hand, and when the locking members are released they will automatically spring into locking position, and retain the sash in the position to which it has been adjusted.

Obviously the sash lock practically acts as a sash weight, prevents rattling, and when the lock is applied to the bottom sash, which is usually the case, although a lock may also be carried by the top sash, it acts as a window prop and obviates the necessity of weights.

A sash lock of this kind can be applied to the sash very easily and by any one who is capable of using a screw driver or hammer, and since the various parts are preferably constructed by punch and die work, all castings (usually employed in other constructions of locks) are eliminated.

The invention having been set forth, what is claimed is:—

1. As an article of manufacture, a sash lock comprising a carrying plate, a fastening device to secure the plate to the face of the sash stile, a pair of locking members having locking ends to engage the bottoms of the sash guide grooves of the window frame, means pivoting the locking members to the carrying plate, tensioning means for the locking members, said fastening means for the plate constituting an abutment with which either one of said locking members may engage, to limit the movement of the locking member in case its locking end has been forced into the bottom of the guide groove.

2. As an article of manufacture, a sash lock, comprising a carrying plate, means for fastening the plate to the face of the sash stile, a pair of locking members having locking ends adapted to engage the bottom of the

sash guide groove, means for pivoting the locking members on the carrying plate, fastening devices passing through the pivoting means to additionally secure the lock to the sash stile, said pivoting means acting to prevent the additional fastening means from causing friction between the locking members and the carrying plate when they are moved and tensioning means for the locking members to hold their locking ends in engagement with the guide groove.

3. As an article of manufacture, a sash lock, comprising a carrying plate, means for fastening the plate to the face of the sash stile, a pair of locking members having locking ends adapted to engage the bottom of the sash guide groove, means for pivoting the locking members on the carrying plate fastening devices passing through the pivoting means to additionally secure the lock to the sash stile, said pivoting means acting to prevent the additional fastening means from causing friction between the locking members and the carrying plate when they are moved, tensioning means for the locking members to hold their locking ends in engagement with the guide groove, said first named fastening means for the plate acting as an abutment with which one edge of either of the locking members may engage for limiting the movement of the locking member, in case its locking end has embedded itself into the bottom of the guide groove.

4. As an article of manufacture, a sash lock, comprising a carrying plate, means for fastening the plate to the face of the sash stile, a pair of locking members having locking ends adapted to engage the bottom of the sash guide groove, means for pivoting the locking members on the carrying plate, fastening devices passing through the pivoting means to additionally secure the lock to the sash stile, said pivoting means acting to prevent the additional fastening means from causing friction between the locking members and the carrying plate when they are moved, tensioning means for the locking members to hold their locking ends in engagement with the guide groove, said tensioning means comprising a bowed spring, the bowed portion of which contacts with the first named fastening means to hold the tensioning means in position.

5. As an article of manufacture, a sash lock, comprising a carrying plate, means for fastening the plate to the face of the sash stile, a pair of locking members having locking ends adapted to engage the bottom of the sash guide groove, means for pivoting the locking members on the carrying plate, fastening devices passing through the pivoting means to additionally secure the lock to the sash stile, said pivoting means acting to prevent the additional fastening means from causing friction

1
between the locking members and the carrying plate when they are moved, tensioning means for the locking members to hold their locking ends in engagement with the guide groove, said tensioning means comprising a bowed string, the bowed portion of which contacts with the first named fastening means to hold the tensioning means in position, said first named fasten-

ing means for the plate acting as an abutment with which one edge of either of the locking members may engage for limiting the movement of the locking member, in case its locking end has embedded itself into the bottom of the guide groove. 10

15 In testimony whereof I hereunto affix my signature.

HOWARD B. SMITH.
